UNITED STATES PATENT OFFICE.

SYLVESTER WILBURN AND THOMAS E. SMITH, OF TUNIS, TEXAS.

WIRE-FASTENER.

No. 874,552.

Specification of Letters Patent.

Patented Dec. 24, 1907.

Application filed September 9, 1907. Serial No. 392,035.

To all whom it may concern:

Be it known that we, SYLVESTER WILBURN and THOMAS E. SMITH, citizens of the United States, residing at Tunis, in the county of Burleson and State of Texas, have invented certain new and useful Improvements in Wire-Fasteners; and we do declare the following to be a full, clear, and exact description of the invention, such as will enable others skilled in the art to which it app- 10 pertains to make and use the same.

This invention relates to improvements in wire fasteners for telegraph poles.

The object of the invention is to provide a 15 fastener of this character by means of which telegraph or telephone wires or any other form of cables may be quickly fastened to the arms of the telegraph poles without the use of tie wires.

20 A further object is to provide a device of this character by means of which the wires will be automatically clamped into engagement with the fastener.

With the foregoing and other objects in 25 view, the invention consists of certain novel features of construction, combination and arrangement of parts, as will be hereinafter described and claimed.

In the accompanying drawings, Figure 1 is 30 a side view of the fastener showing the same applied to the arm of a telegraph pole; Fig. 2 is a vertical sectional view through the arm of a telegraph pole showing a side view of the fastener at right angles to that shown in Fig. 35 1; and Fig. 3 is a vertical sectional view of the fastener taken on the line 3—3 of Fig. 1.

Referring more particularly to the drawings, 1 designates the fastener which comprises a head 2 having on its lower end an angular arm-engaging flange 3. Formed integral with the head 3 is a downwardly projecting fastening bolt or shank 4 which is adapted to be inserted through the arm of the telegraph pole and is threaded on its 45 lower end to receive a clamping nut 5.

On the upper end of the head 2 is formed a reduced clamp-engaging portion 6 upon which is adapted to be secured a wire clamp 7 comprising a bracket having a horizontally disposed base portion 8, a tapered opening formed therein to receive the reduced upper end 6 of the head 2. Around said reduced upper end 6 of the head and the tapered hole in the base 8 is arranged a sleeve of insulating material 9 by means of which the

clamp 7 is insulated from the head and shank of the fastener.

The upper surface of the base 8 is slightly curved or rounded off at its outer edges and is provided with a series of corrugations 10. 60 One end of the base plate 8 is curved upwardly to form a detent 12 while at the opposite end of the plate is formed an upwardly projecting right-angular arm 13 to the upper end of which is pivotally connected the movable member 14 of the clamp.

The member 14 comprises a head 15, the lower side of which is slightly curved and is provided with a series of corrugations 16, said corrugated lower side of the member 14 70 being adapted to coact with the corrugated upper side of the base-plate 8 whereby a wire is firmly clamped between the same. The upper end of the member 14 is provided with a handle 17 by means of which said member 75 may be swung laterally to disengage the head 15 from the wire, thus releasing the same.

In practice, the wire to be fastened is stretched across the curved upper surface of the base plate 8 and the clamping member is 80 engaged with the upper side of the wire, after which the stretched wire is slackened to permit the same to retract to a slight degree, said retraction causing the upper member of the clamp to be drawn downwardly, thus 85 binding the same into tight engagement with the wire and holding the latter between the corrugated surface of the head 15 and the curved upper side of the base plate 8.

From the foregoing description, taken in 90 connection with the accompanying drawings, the construction and operation of the invention will be readily understood without requiring a more extended explanation.

Various changes in the form, proportion 95 and the minor details of construction may be resorted to without departing from the principle or sacrificing any of the advantages of the invention, as defined by the appended claims.

Having thus described my invention, what I claim as new, is:—

1. A fastening device for telegraph wires and the like comprising a head, means to secure the same to the arm of a telegraph 105 pole, a clamping member secured to and insulated from said head, means whereby the wire may be automatically fastened by said clamp, substantially as described.

2. A wire fastener of the character de- 110

scribed comprising a head, a shank or bolt formed on said head whereby the same is secured to the arm of the telegraph pole, a clamping device secured to and insulated from said head, said clamping device comprising a base portion having a corrugated upper surface and a pivotally mounted clamping head having a corrugated lower surface to coact with the corrugated surface 10 of said base, substantially as described.

3. A wire fastener of the character described, comprising a head having an annular flange on its lower end, a fastening bolt or shank formed on the lower end of said head, 15 a clamping device secured to and insulated from the upper end of the head, said clamping device comprising a base having a curved and corrugated upper surface, an upwardly projecting detent formed on one end of said

base plate, an upwardly projecting arm 20 formed on the other end of the base plate, a clamping member pivotally mounted on said arm, a head formed on the lower end of said member, said head having a curved and corrugated lower surface to coact with 25 the corrugated upper surface of the base plate and a handle portion on the upper end of said pivoted clamping member, substantially as described.

In testimony whereof we have hereunto set our hand in presence of two subscribing witnesses.

SYLVESTER WILBURN.
THOMAS E. SMITH.
